MAGNETRON APPARATUS

Rene A. Braden, Collingswood, N. J., assignor to
 Radio Corporation of America, a corporation of
 Delaware

Application July 22, 1936, Serial No. 92,051

6 Claims. (Cl. 250—36)

This invention relates to magnetron apparatus and more particularly to a magnetron which employs a permanent magnet with an adjustable shunt for varying the magnetic field.

5 A magnetron is a device in which a cathode and cylindrical shape anode are concentrically mounted within an evacuated envelope. A magnetic field is applied so that its lines of force surround and are substantially parallel to the cathode. Under the influence of the magnetic field electrons emitted from the cathode follow 10 curved paths toward the anode. If a suitable resonant circuit is connected between cathode and anode, oscillatory currents of ultra high frequency may be established in the resonant circuit. The frequency or wave length of the resonant circuit and the magnetic field must be properly 15 related to establish the optimum oscillatory current. The ratio between the field and the wave length is approximately such that the wave length in centimeters equals twelve thousand divided by the magnetic field in gauss.

An electromagnet may be readily used to establish the magnetic fields of desired density, but 20 an electromagnet, together with its power supply, is not entirely suitable for portable equipment. While a permanent magnet may be substituted for the electromagnet, suitable provision should be made for varying the field strength at the 25 pole of the permanent magnet. This invention contemplates a permanent magnet for a magnetron provided with suitable means for varying the density of the applied magnetic field.

One of the objects of this invention is to provide 30 a permanent magnet structure for a magnetron.

Another object is to provide a permanent magnet with means for adjusting the density of the magnetic field at the pole pieces to thereby control 35 a magnetron.

A further object is to provide a single control means for adjusting the density of the magnetic field and the frequency of the resonant circuit of a magnetron.

40 The invention may be best understood by reference to the accompanying drawings in which Figs. 1 and 2 represent, respectively, end and side elevational views of one embodiment of my invention.

45 Fig. 3 is a schematic diagram of a magnetron and a view, in perspective, of a permanent magnet with a variable shunt, and tunable output circuit which are adjusted by unicontrol means, and

50 Fig. 4 is a side elevational view of a permanent

magnet with an adjustable shunt for controlling the magnetic field applied to a magnetron device.

In describing the several figures, the same reference numerals will be used to indicate similar parts. Referring to Figs. 1 and 2, on a suitable base 1 is pivotally mounted a non-ferrous U-shaped bracket 3. The bracket may be locked in position by the bolt 5 which projects through the base 1. A pair of pole pieces 7—7 of soft iron are secured to the ends of the U-shaped bracket. The pole pieces 7, 7 are joined to one or more U-shaped permanent magnets 9.

A pair of face plates 11, 11 of ferrous metal are clamped to either side of the pole pieces by bolts 13. The face plates 11—11 are completed at the top by non-ferrous plates 15 which are secured to the face plates by bolts 17, rivets or the like. The upper ends of the non-ferrous plates are bent at right angles and form the bearings 19 for adjusting screws 21. The adjusting screws 21 are maintained in the bearing 19 by suitable shoulders which take up the end thrust. Adjusting knobs 23 are secured to the screws 21.

A pair of adjustable magnetic shunts 25 are 25 engaged by the screws 21. Suitable projections 27 at the ends of each shunt engage the sides of the face plates 9 and thereby form guides for the vertical adjustment of the shunts. The magnetic force is sufficient to securely hold the shunts 30 to the surfaces of the face plates 9. It will be observed that the lower central part of each shunt is cut away to prevent the shunt from striking the magnetron tube 29 which is positioned between the pole pieces 7 and supported by a pair 35 of brackets 31.

The magnetron tube envelope may be flattened adjacent the pole pieces to thereby bring the pole pieces close to the anode and cathode elements. The details of the magnetron electrode arrangement have been omitted in Figs. 1 and 2 but may be seen in Fig. 3.

In the operation of the shunts in Figs. 1 and 2, the permanent magnets establish a strong field between the pole pieces when the shunts are at 45 the uppermost position. When the shunts are moved to their lowermost position, a substantial portion of the magnetic lines of force formerly existing between the pole pieces are now transferred to the shunts and thus the magnetic 50 density between the pole pieces is minimized. The actual adjustment is effected by rotating the adjusting screws 21 which are threaded into the shunts. It should be understood that a single shunt may be used, or two shunts may be used 55

with a suitable unicontrol or with separate controls.

In Fig. 3 a single permanent U-shaped magnet 33 is shown. A pair of pole pieces 35 are secured 5 to the ends of the magnet. A magnetic shunt 37 is adjustably arranged on the surface of the magnet. The shunt may be equipped with guides, not shown, to prevent horizontal movement and permit vertical adjustment. The vertical adjustment is accomplished by an adjusting screw 39 which is supported by a bearing in a bracket 41. Collars 43 attached to the screw prevent motion along its axis. An adjusting knob 45 may be secured to the screw 39. A pulley 47, whose 10 function will be described below, is also attached to the screw.

Within a magnetron envelope 49 are concentrically supported a cathode 51 and a pair of split cylindrical anodes 55. The cathode is connected to a battery 57, and the anodes are connected to the conductors of a transmission line 59. The transmission line terminates in a dipole antenna 61. An anode battery 63 is connected between the cathode battery and the central point of the dipole antenna. The positive terminal of the battery is connected to the dipole. 20

The transmission line 59 forms the resonant output circuit of the magnetron. The oscillatory frequency of the transmission line may be adjusted by varying its effective length by means of a pair of "trombones" 65 or other suitable means. As pointed out above, the field density and the optimum frequency of oscillation are related. Therefore, the length of the transmission line 59 25 and the adjustment of the magnetic shunt may be related. This relation will not be linear and may vary for different magnets and different magnetrons.

The unicontrol for the shunt and the transmission line is effected by connecting the screw 39 through a small pulley 47 and belt 67, or any type mechanical coupling of suitable radio, to a relatively larger pulley 69 which is fastened to a shaft 71. The shaft 71 is mounted on bearings 73 which are supported by any appropriate means. A disc 75 is secured to the shaft and a cam slot 77 is cut in the disc. The actual shape of the cam slot may best be determined experimentally by noting the position of the "trombones" 65 for a series of adjustments of the magnetic shunts. A cam follower 79 is located in the slot and secured to the "trombones" by an insulated link 81. The link may be supported by guides, not shown. 40

The knob 45 turns the adjusting screw 39 55 which positions the shunt 37 and at the same time through the connecting belt 67 tunes the disc 75. By means of the cam slot 77 and connecting link 81 the effective length of the transmission line is adjusted to correspond with the optimum shunt position. Thus the uni-control between the magnetic shunt and resonant output circuit is made practical.

Instead of sliding the shunts as illustrated in Figs. 1, 2 and 3, the arrangement of Fig. 4 may be employed. In Fig. 4 a plurality of U shaped permanent magnets 83 are clamped together by non-magnetic face plates 85. The upper ends of the face plates are bent to form a support for the member 87 which carry the magnetic shunts 89. The members 87 are connected by a biasing spring 91. The spring draws the shunt carrying members inwardly and causes them to engage the cam 93 which is rotatably supported within the permanent magnets. As the cam is rotated 70 the shunts are displaced with respect to the pole

pieces 95 which are positioned at the ends of the U shaped magnets. The maximum air gap between the shunt and pole pieces corresponds with maximum field intensity between the pole pieces. The minimum air gap between the shunts and pole pieces corresponds with minimum flux density between the pole pieces. The arrangement of Fig. 4 may be used as indicated in Fig. 3 to effect unicontrol adjustment of the shunt and resonant circuit. 10

Thus I have described a magnetron device which may be used as an oscillator, detector or amplifier. The magnetic field is supplied by a permanent magnet which includes an adjustable magnetic shunt. Varying the position of the shunt varies the magnetic field applied to the magnetron. This variation in field changes the oscillation frequency, if the tube is operating as an oscillator, or changes the frequency to which it is sensitive if it is operating as a detector or 15 amplifier.

When used as a detector or amplifier the incoming waves are impressed on the antenna, and resulting output currents in the anode circuit are impressed on a suitable signal responsive element. 20 When used as an oscillator, the oscillatory currents are impressed on the antenna. Suitable means are provided for unicontrol of the tunable circuit and the magnetic shunt. 25

I claim as my invention:

1. A tunable magnetron oscillator which comprises a tube having cathode and anode electrodes and means including a variable magnetic field for producing oscillations in said tube which depend in frequency on the strength of said magnetic field, a variable tuning means connected between said electrodes, and unicontrol means for simultaneously varying the magnetic field and said tuning means to keep the frequency of the oscillations generated and the frequency of the tuned circuit substantially the same. 40

2. A tunable magnetron including in combination a tube having cathode and anode electrodes and means including an adjustable magnetic field for producing electronic oscillations in said tube, said oscillations having a frequency dependent upon the adjustment of said field, a variable tuning means connected between said electrodes, and a unicontrol means for simultaneously varying said tuning means and adjusting said field to keep the frequencies of said oscillations and said tuning means substantially the same. 45

3. A tunable magnetron including in combination a tube having cathode and anode electrodes and means including a magnetic field for producing electronic oscillations in said tube; means for varying the strength of said field and thereby varying the frequency of said oscillations; a tunable circuit connected between said electrodes; and a unicontrol means for varying said field varying means and varying said tunable circuit to keep the frequency of said oscillations and the frequency of said circuit substantially the same. 55

4. A tunable magnetron oscillator including in combination a tube having cathode and anode electrodes and means including a variable magnetic field for producing oscillations in said tube, said oscillations having a frequency varying as a function of the strength of said field, a variable tuning means connected to said electrodes, said variables having different rates of variation for equal increments of adjustment, and a unicontrol means for simultaneously varying said magnetic field and said tuning means to keep the frequency of the oscillations generated and the 70 75 75

frequency of the tuned circuit substantially the same.

5. In a magnetron oscillator, the combination of a magnetron including cathode and anode electrodes, a tunable circuit connected to said electrodes, means for tuning said circuit, means for establishing a magnetic field about said electrodes, means for varying the strength of said field whereby oscillations of a frequency dependent on 10 said field strength are generated in said tube, and unicontrol means coupling said field varying means and said tuning means whereby each may be adjusted simultaneously to thereby effect substantially optimum operation of said magnetron 15 and said circuit at the same frequency.

6. In a magnetron oscillator, the combination of a magnetron including cathode and anode electrodes, a tunable circuit connected to said electrodes, means for tuning said circuit, a permanent magnet for establishing a magnetic field about 5 said electrodes, a shunt for varying the strength of said field whereby oscillations of a frequency dependent on said field strength are generated in said tube, and unicontrol means coupling said shunt means and said tuning means whereby 10 each may be adjusted simultaneously to thereby establish substantially optimum oscillations in said magnetron and in said circuit at the same frequency.
